INVENTOR
HARRY J. STEVENS.

BY Chas E. Townsend

ATTORNEY

UNITED STATES PATENT OFFICE.

HARRY J. STEVENS, OF OAKLAND, CALIFORNIA.

LID-RACK.

1,359,125.

Specification of Letters Patent. Patented Nov. 16, 1920.

Application filed April 14, 1920. Serial No. 373,831.

To all whom it may concern:

Be it known that I, HARRY J. STEVENS, a citizen of the United States, residing at Oakland, in the county of Alameda and State of California, have invented a new and useful Improvement in Lid-Racks, of which the following is a specification.

This invention relates to a rack and particularly pertains to a device of that character adapted for receiving lids, books and other articles. It is the principal object of the present invention to provide a rack which may be inexpensively manufactured and which when produced will form a compartment within which articles may be stored and from which these articles may be easily withdrawn. This is true when the rack is used to receive lids of different diameters, as it is an object of this invention to provide a rack which will hold lids of different diameters in spaced relation to each other so that they may be separately removed in an easy manner, at the same time be fitted with means to prevent it from rattling 25 against the wall.

The present invention contemplates the use of a wire frame of triangular shape, upon which other wires are fastened and around which they are wrapped to form a rack having a substantially triangular opening in the front face thereof to permit easy access to the various articles therein, the main frame being fitted with loop members which extend rearwardly and rest against 35 the wall to hold the main frame in a spaced relation to the wall while it is hung upon a central top hanging loop.

The invention is illustrated by way of example, in the accompanying drawings, in 40 which:—

Figure 1 is a view in perspective, showing the complete rack.

Fig. 2 is a view in front elevation, showing the rack and further indicating a plurality of lids disposed therein.

Referring more particularly to the drawings, 10 indicates a triangular back frame. This frame comprises a horizontal length of wire 11, the ends of which bend downwardly and inwardly to form two side lengths of wire 12 and 13. These wires are secured to a lower cross wire 14 thereby forming a substantially triangular back frame. The cross wire 14 is bent forwardly at points near its 50 juncture with the wires 12 and 13. These parts are indicated at 16 and 17 and are

shown as extending horizontally a distance representing the depth of the lid rack. These wires are then bent upwardly and inwardly at a single vertical plane and then passed vertically in spaced parallel relation to each other as indicated at 18 and 19, after which the wires are bent in opposite directions from each other so that portions 20 and 21 will extend parallel to the back wire 11 and 65 in substantially the same horizontal plane therewith. The ends of the lengths of wire 20 and 21 are then bent rearwardly and are caused to engage the side wires 12 and 13 of the back frame. A vertically reinforcing 70 wire 22 extends from the wire 11 to the wire 14 and is firmly secured to both of these wires. This reinforcing wire also extends forwardly as indicated at 23 and then upwardly in the same vertical plane as the 75 lengths of wire 18 and 19. The upper terminating end of the wire 23 is secured to a binding wire 24. This wire forms a rectangle and extends horizontally embracing the wires 12, 13, 18 and 19. The ends of 80 the wire 24 are secured to the vertical reinforcing wire 22 while the wire is further fastened by being soldered at the points of its intersection with the wires 12, 13, 18 and 19. In order that the rack may be suspended 85 from a hook or pin upon the wall an eye 25 is bent in the vertical member 22 as clearly shown in Fig. 1 of the drawings. This eye has a V-shaped opening through which the pin may extend and by which the 90 pin will be engaged to act to limit the swinging movement of the rack. The horizontal wire 11 is formed with outwardly extending loops 26. These loops extend horizontally and occur at points near the upper corners 95 of the back frame. By this means the rack may be supported from the surface of a wall and will thus prevent rattling of the rack and its contents. It will further be observed that the lengths of wire 18, 19 and 100 the intervening portion of wire 24 form an opening in the front of the rack which will permit the lids to be readily reached and removed. It will also be evident that by this arrangement of the rack in a substantially 105 inverted triangular form pot lids varying in diameter may be supported and rendered accessible as shown in Fig. 2.

It will thus be seen that the device here disclosed may be readily made from wire in 110 a simple manner and that the rack will conveniently accommodate lid racks of various

diameters at the same time supporting the rack so that it will not rattle when held against the wall.

While I have shown the preferred form 5 of my invention as now known to me, it will be understood that various changes in the construction, combination, and arrangement of parts may be made by those skilled in the art without departing from the spirit 10 of the invention as claimed.

Having thus described my invention, what I claim and desire to secure by Letters Patent is:

1. A rack comprising a substantially triangular main frame disposed in an inverted position and formed of a continuous piece of wire, a front frame member formed of a continuous piece of wire and secured by its opposite ends to the upper corners of 15 the main frame, and extending outwardly, then downwardly, then outwardly and inwardly in a reverse curve with its lower rods secured to the lower angles of the main frame, to form an open loop panel in front 20 of the rack, a stay wire secured to the upper cross member of the main frame, and extending downwardly through the center thereof and wrapped around the lower cross member of said frame, and carried outwardly and upwardly with its terminal end 25 secured to the lower front cross member of the front frame and having a suspending loop formed near the upper end of its vertical rear portions, and a plurality of horizontal stay members secured to said vertical stay and to the side stays of the main frame, thence bent outwardly and horizontally to 30 engage the sides of the front frame and complete the formation of the rack basket.
2. A rack comprising a substantially triangular-shaped main frame disposed in an inverted position and formed of a continuous piece of wire, a front frame member formed of a continuous piece of wire, and 35 secured by its opposite ends to the upper corners of the main frame and extending outwardly and then downwardly to form a loop open panel in the front of the rack,

a stay wire secured to the upper cross-member of the main frame and extending downwardly through the center thereof to be wrapped around the lower cross-member of said frame and carried outwardly and upwardly to be secured by its terminating ends to the lower cross-member of the loop of 55 the front frame and a plurality of stay members secured to said vertical stay and wrapped around the side stays of the main frame and then led outwardly and inwardly to engage the sides of the front frame and complete the formation of the rack basket, and loop members formed by the terminating ends of the wire forming the front frame member and adapted to space the main frame from the supporting structure. 60

3. A rack comprising a substantially triangular-shaped main frame disposed in an inverted position and formed of a continuous piece of wire, a front frame member formed of a continuous piece of wire and secured by its opposite ends to the upper corners of the main frame and extending outwardly and then downwardly to form a loop open panel in the front of the rack, a stay wire secured to the upper cross-member 70 of the main frame and extending downwardly through the center thereof to be wrapped around the lower cross-member of said frame and carried outwardly and upwardly to be secured by its terminating ends 75 to the lower cross member of the loop of the front frame, and a plurality of stay members secured to said vertical stay and wrapped around the side stays of the main frame and then led outwardly and inwardly to engage the sides of the front frame and complete the formation of the rack basket, and loop members formed by the terminating ends of the wire forming the front frame member and adapted to space the main frame from the supporting structure and a supporting loop formed by the upper terminating end of the central stay wire. 85

In testimony whereof have hereunto set my hand.

HARRY J. STEVENS.
